INSTRUMENT FOR PROVIDING A PRINT OF AN OPTICAL LENS ELEMENT

David R. Lierman, 8 Alder Court, Champaign, Ill.

Filed Jan. 24, 1962, Ser. No. 68,496

Term of patent 14 years

(Cl. D61—1)

Fig. 1

Fig. 2

Fig. 3

FIG. 1 is a perspective view of an instrument for providing a print of an optical lens element, embodying my new design;

FIG. 2 is a front elevational view thereof;

FIG. 3 is a left-side elevational view thereof;

FIG. 4 is a right-side elevational view thereof;

FIG. 5 is a top plan view thereof; and

FIG. 6 is a top plan view of the instrument base taken generally on the line 6—6 of FIG. 2.

The rear of the instrument, not shown, is plain and unornamented.

I claim:

The ornamental design for an instrument for provid-

ing a print of an optical lens element, substantially as shown and described.
